United States Patent Office

Des. 187,889
Patented May 10, 1960

187,889

HOLDER FOR A MILK CARTON OR THE LIKE

George Zaccaro, West Covina, Calif.

Application January 11, 1960, Serial No. 59,002

Term of patent 14 years

(Cl. D58—26)

Fig. 1 is a perspective view of a holder for a milk carton or the like, showing my new design.

Fig. 2 is a bottom plan view thereof.

I claim:

The ornamental design for a holder for a milk carton or the like, substantially as shown.
